(57) **CLAIM**

The ornamental design for a seat, as shown and described.

DESCRIPTION

FIG. 1 is a left front perspective view of a seat showing my new design;

FIG. 2 is a top view thereof;

FIG. 3 is a left side elevational view thereof;

FIG. 4 is a right side elevational view thereof;

FIG. 5 is a front elevational view thereof; and,

FIG. 6 is a rear elevational view thereof.

The views of the seat not shown form no part of the claimed design. The broken lines depicting joint wraps, ornamentation, spreader vertical members, seat and seat back represent environmental elements only and form no part of the claimed design. The separations and brackets indicate, for ease of illustration, that the precise width of the seat is not claimed.
